UNITED STATES PATENT OFFICE.

WILLIAM H. GESELL, OF MONTCLAIR, NEW JERSEY.

RECEPTACLE AND CLOSURE THEREFOR.

Application filed April 26, 1922. Serial No. 558,701.

To all whom it may concern:

Be it known that I, WILLIAM H. GESELL, a citizen of the United States, residing at Montclair, in the county of Essex and State 5 of New Jersey, have invented a certain new and useful Receptacle and Closure Therefor, of which the following is a specification.

This invention relates to receptacles, and is more particularly directed to a novel receptacle closure so constructed that it will 10 not only serve the purpose of sealing the outlet to the receptacle but, when prepared for the market, will provide a chamber in which directions for the use of the material 15 contained in the receptacles may be housed. After the article has come into the hands of the ultimate purchaser and the closure removed, the directions may be taken therefrom and read and thereafter the closure 20 employed as a measuring cup to measure out predetermined quantities of the contents of the receptacle. When subsequently not in use, the receptacle may be sealed by returning the closure thereto.

25 The present invention thus provides a receptacle having a closure so formed as to provide convenient means for housing printed instruction sheets or directions and also a convenient measuring receptacle. The capability of the closure to house 30 printed instructions is important since it enables the manufacturer to place before the purchaser more clear and explicit directions for the use of the contents of the containers 35 than could be printed upon the surface of containers, which, in many cases, are so small that any printed label applied to the exterior thereof must necessarily be small and the type used so fine that it cannot be 40 read by persons with defective sight. When the present invention is employed, however, the label on the exterior of the container may contain relatively large printing, embodying a brief résumé of the directions, 45 while clear, full and explicit directions may be printed on a direction sheet adapted to be folded and housed within the closure in concealed position until the closure is removed by the ultimate purchaser.

50 In the preferred manner of carrying out the present invention, the container is provided with a relatively long threaded neck or outlet mouth and the closure embodies a threaded cap adapted to be screwed onto said mouth. The cap, however, is of less 55 depth than the height of the mouth and the

base of the cap is flared outwardly and downwardly to form an inverted cup having an open bottom. When the cap is screwed down tight upon the threaded mouth of the 60 container so as to seal the open top thereof, the open side of the cup comes to a seat upon the top of the container at the base of the neck thereof and forms, interiorly of the inverted cup, a closed annular chamber in 65 which the direction sheet is adapted to be housed. In the preferred form of the invention, the cap is adapted to have threaded engagement with a threaded neck but, in practice, a frictional sliding or bayonet joint 70 connection, or other form of connection, may be employed without departing from this invention.

75 Features of the invention, other than those adverted to, will be apparent from the hereinafter detailed description and claims, when read in conjunction with the accompanying drawings.

80 The accompanying drawings illustrate one practical embodiment of the invention, but the construction therein shown is to be understood as illustrative, only, and not as describing the limits of the invention.

85 Figure 1 is a side elevation of a container and closure, assembled, embodying the present invention, one lateral half of the closure being shown in central section.

90 Figure 2 is a view similar to Figure 1 but illustrating the closure removed from the container; and

95 Figure 3 is a bottom perspective view of the closure removed from the container.

100 Referring to the drawings, 1 designates a container which, for the purpose of illustration, is shown in the form of a cylindrical can. The can is provided at its top with a discharge spout embodying an outlet mouth or neck 2, the upper portion of which is threaded as at 3. In order that the container may be efficiently emptied, that portion 4 of the neck of the container intermediate the top of the cylindrical portion 5 and the threaded mouth 3 is shown as substantially frusto-conical but, in practice, a cylindrical threaded neck may extend 105 directly from the top of the cylindrical portion 5 and the frusto-conical portion 4 may be omitted.

110 The closure for the container described embodies an interiorly threaded cap 6 adapted to screw onto the threaded neck 3 of the container and in the base of this cap a disc

7 of cardboard, cork or other material may be positioned so that, when the cap is screwed tightly onto the neck of the container, a tight seal will result. The cap 6 is of a depth considerably less than the height of the neck and the base of such cap is flared outwardly as at 8 to form a base flange, the outer periphery of which is formed with a depending flange or skirt 9. The full depth of the closure 10 is substantially equal to the length of the neck of the container so that when the threaded cap portion 6 of the closure is screwed onto the threaded neck portion 3 of the container to form a tight seal for the latter, the lower edge of the skirt 9 will be brought into engagement with the upper surface of the can and form a tight joint at this point. In practically carrying out the invention, the base flange 8 is preferably 20 made substantially flat and the parts are so proportioned that the lower edge of the skirt 9 will engage with the top of the can shortly before the screw cap becomes seated so that, as the screw cap is turned down tightly, the base flange 8 will be slightly flexed so as to force the skirt firmly against the top of the can and provide a tight joint between these parts.

It will be apparent that, when the parts 30 are assembled after the manner shown in Figure 1, a closed annular chamber 10 will be formed between the can and the closure.

In packaging goods for the market, the can is first filled and the closure is then applied. However, before applying the closure, a printed direction sheet, folded into relatively small dimensions, as shown at 11, is positioned within the cup portion of the closure, as best shown in dotted lines in Figure 3. The closure is now screwed into position and serves not only to seal the can but also to house the direction sheet 11 in concealed position.

When the ultimate purchaser removes the closure the direction sheet is exposed and may be removed and read, after which the closure may be held in inverted position and employed as a measuring cup. In practice, the parts are so proportioned that the cup 45 will be of a size well adapting it to measure predetermined quantities of the material contained in the can. The capacity of the closure, for use as a measuring cup, will of course depend upon the height of the neck 50 of the can and the consequent depth of the closure and also upon the diameter of the cup portion of the closure. These dimensions can be calculated so that the cup will hold a predetermined quantity of the material. If desired, the skirt 9 may be provided with graduations 12 to enable accurate measuring of different quantities of the material, as shown in Figure 2.

In the foregoing specification, I have set 65 forth the preferred embodiment of the in-

vention. It will be understood, however, that details of the construction shown in the drawings may be changed, as by the substitution of equivalents, without departing from the present invention. For example, 70 the can has been referred to as cylindrical in shape but the invention may be associated with a can or receptacle of any shape. Moreover, the cap has been described as having threaded connection with the neck of the 75 can, while, in practice, a sliding fit may be provided between these parts or a bayonet joint engagement may be employed. For these reasons, the present invention is not 80 restricted to the specific structural details illustrated but is to be understood as broadly 85 novel as is commensurate with the appended claims.

Having thus fully described the invention, what I claim as new and desire to secure by Letters Patent:

1. A device of the character described embodying a container provided at its top with an upstanding threaded outlet spout, projecting above the top of the body of the container, a threaded cap adapted to screw onto the outlet spout for the purpose of sealing the same and mounting the cap on the spout against inadvertent displacement, said cap being provided at its bottom with an outwardly extending substantially flat base flange, the outer periphery of which is provided with a depending skirt adapted to engage with the top of the container before the cap becomes fully seated on the spout thereof, whereby the bringing of the cap into fully seated position flexes the base flange and causes the skirt to be forced tightly against the top of the container. 95

2. A device of the character described embodying a container provided at its top with an upstanding outlet spout, a cap adapted to engage and grip the outlet spout for the purpose of sealing the same and to hold the cap against inadvertent displacement, said cap being provided at its bottom with a substantially flat base flange, the outer periphery of which is provided with a depending skirt adapted to engage with the top of the container before the cap becomes fully seated on the spout thereof, whereby the bringing of the cap to fully seated position flexes the base flange and causes the skirt to be forced tightly against the top of the container to form within the skirt and below the base 100 flange a closed annular chamber adapted to contain an instruction sheet. 115

3. A device of the character described embodying a container provided at its top with a threaded outlet spout, projecting above the top of the body of the container, a cylindrical measuring cup, open at its bottom and closed at its top, and provided centrally of its top with an upstanding interiorly threaded imperforate cap adapted to be 120 125 130

screwed onto the threaded spout of the container for the purpose of sealing the same and simultaneously mounting both the cap and cup on the container against inadvertent displacement, said measuring cup being of such depth that, when the screw cap portion thereof is screwed onto the threaded spout of the container, the open side of the

measuring cup will engage with the top of the container and form a closed annular chamber around the lower portion of the spout.

In testimony whereof I have signed the foregoing specification.

WILLIAM H. GESELL.
